Patented Sept. 14, 1926.

1,599,502

UNITED STATES PATENT OFFICE.

HERMANUS THOMASSEN, OF VELP, NETHERLANDS.

CENTRIFUGAL SEPARATOR.

Application filed November 11, 1924, Serial No. 749,186, and in Germany May 27, 1924.

My copending application for Patent Nr. 693,270 relates to a process for removing impurities from paper pulp or other fibrous material by means of a centrifugal separator running at such speed that the pulp accumulates in a substantially cylindrical layer around the axis of rotation, whereby the heavier impurities are thrown out against the wall of the drum so as to remain in the separator, whereas the purified mass is discharged over the top edge of the drum. Secured to the said top edge is an inwardly projecting ring, the width of which determines the thickness of the layer of pulp formed and, consequently, the time during which the mass is subjected to the centrifugal action, whereas a second ring concentric with the axis of rotation but disposed at some distance from the wall of the drum retains the lighter impurities. By this process it is possible to produce in a minimum of time perfectly pure paper pulp.

My present invention relates to a centrifugal separator which is exceptionally suitable for carrying the said process into practice. The drum of this separator consists of superposed, concentric, cylindrical sections of increasing diameter, so that in elevation the drum is stepped. To the top edge of each drum section I secure the ring, the width of which determines the thickness of the cylindrical layer of pulp. For separating out the lighter impurities, it suffices in most cases to provide only the upper drum section with a ring a certain distance inwardly from its wall, which ring may be slightly dished or curved in cross section.

In a centrifugal separator according to my present invention the coarse impurities are separated out in the lowermost section of the drum, whereas the higher sections serve to separate the smaller impurities. Such a stepped centrifugal machine offers the advantage that the completeness of the separation can be checked by the absence of impurities against the inner wall of the top section.

The annexed drawing illustrates, by way of example only, a centrifugal separator comprising five sections, Figure 1 being a vertical section and Figure 2 a plan view of the machine. Figure 3 shows on an enlarged scale the vertical section of part of the stepped wall of the drum.

Secured to a hollow vertical shaft 1 is a bottom 2, which supports a drum consist-

ing of five superposed cylindrical sections 3. The shaft 1 is driven through mitre wheels 5, 6 by a belt pulley 4. To the pulp, which is continuously supplied through a central feed pipe 7 having a flared mouth 8 a relatively small distance above the bottom 2, rapid rotary motion is imparted by vanes, arms or impellers 9 secured to the shaft 1, whereby it is thrown at high radial speed against the wall of the drum, so that by the impact part of the impurities associated with the fibres is released therefrom. In the first or lowermost section the pulp thus forms a cylindrical layer, the thickness of which corresponds to the width of the ring 10 secured to the top edge of this section. As the pulp is delivered by the feed pipe 7, the partly purified mass is forced over the lowermost ring 10 into the second drum section, where it is again thrown against the cylindrical wall so as to release part of the impurities not yet removed in the lowermost section. Besides, the mass is here subjected to increased centrifugal action because the diameter of the second section exceeds that of the first one. The mass is thus successively passed through the third, the fourth and the fifth section of the drum, it being understood that in each section it is temporarily retained by a ring 10 and thereafter forced over this ring until the completely purified mass is discharged into a stationary container 12 provided with an outlet 13.

One single ring 11 placed inside the top section at a small distance from the cylindrical wall thereof retains the lighter impurities, but it should be well understood that two, three or more of the sections may be provided with such a ring 11.

The gearing and the drum are enclosed by casings 14 and 15, respectively.

The number of drum sections used depends upon the percentage and the nature of the impurities present in the pulp, upon the desired quality of the purified material, etc.

It has been found in practice that a centrifugal separator having only two sections gives already much better satisfaction as regards the purifying of the pulp than a machine having an ordinary, i. e. non-stepped drum.

What I claim is:—

1. A centrifugal separator comprising a drum having superposed unperforated

cylindrical sections of increasing diameter, a ring projecting inwardly from the upper edge of each of said sections to prevent the discharge of heavier material, and an annular member mounted in at least one of the sections of the drum to prevent the discharge of lighter material, and spaced from the internal wall of said section to permit the discharge of material of predetermined weight.

2. A centrifugal separator comprising a drum having superposed unperforated sections of increasing diameter, a ring projecting inwardly from the upper edge of each of said sections to obstruct the passage of heavy materials, and an annular member mounted within the upper section and spaced from the inner wall of said section and from the inwardly projecting ring therein to obstruct the passage of lighter

materials and to permit the passage of materials of medium weight.

3. A centrifugal separator comprising a drum having superposed unperforated sections of increasing diameter, central feed 25 means for supplying the material to the lower section, an internal annular ledge formed at the upper extremity of each section to obstruct the passage of the heavier materials, an annular member mounted 30 within the upper section and spaced from the inner wall thereof and from the adjacent annular ledge to obstruct the passage of lighter materials, and an annular receiver for the material of medium weight 35 passing between the said ring and the adjacent ledge.

In testimony whereof I affix my signature.

HERMANUS THOMASSEN.
